SOTA, A CORPORATION OF DELAWARE

MERCURY SWITCH

Application filed November 24, 1928. Serial No. 321,570.

This invention relates in general to mercury switches and more particularly to the mercury switch of the type having a protective element of arc resisting material for receiving and withstanding the shock and strains resulting from arcing and from the high temperature and rapid temperature fluctuations incident thereto.

One of the principal objects of the present invention is to provide a mercury switch of this character which is of simple and durable construction, reliable and effective in operation and easy and comparatively inexpensive to manufacture.

In carrying out these purposes, a mercury switch is constructed with an outer envelope of soft glass or other suitable material in which a protective element of hard glass, quartz, porcelain, or other arc resisting material is assembled. The outer envelope has in its upper portion an outwardly directed enlargement in which one end of the protective element is disposed. Yieldable supporting means such as a ring of cement or the like is interposed between the inner wall of the outwardly directed enlargement of the outer envelope and the protective element whereby the protective element is yieldably although directly suspended upon the outer envelope. Obviously, the particular construction employed for effecting this yieldable suspension directly on the outer envelope may be varied. The lower end of the protective element provides a well receiving a portion of a body of mercury placed in the outer envelope. The body of mercury also has a shiftable portion in the outer envelope which makes and breaks contact with the portion in the well on a surface of the protective element.

Electrodes are sealed through the outer envelope and immersed in the mercury in the well and in the shiftable portion of the mercury respectively. The protective element is fashioned to provide a protecting shield for the electrode projecting down into the mercury in the well to prevent direct contact between the shiftable portion of the mercury and such electrode. This shielding is effected by cutting spaced slots in the protective element and depressing the portion there-

of between the slots inwardly towards the electrode to be protected. Of course, the protective element must be heated and rendered plastic to permit of this construction in the first instance. This structure of the protective element not only provides the shield but also provides the opening through which the portions of the mercury unite and divide and the surface on which the make and break occurs.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view in central vertical longitudinal section showing a mercury switch embodying the present invention and illustrating the same as positioned when the portions of the mercury are divided and the circuit controlled by the switch is broken;

Figure 2 is a similar view illustrating the switch as positioned when the portions of the mercury are united;

Figure 3 is a view in transverse vertical section taken on line 3-3 of Figure 2; and

Figure 4 is a view in horizontal section taken on line 4-4 of Figure 2.

Referring to the drawings, the numeral 1 designates an outer envelope which may be constituted of soft glass or any other suitable material. Within the outer envelope 1 a protective element 2 of arc resisting material is provided and may be constituted of hard glass, quartz, porcelain, aluminum oxide, or any other suitable arc-resisting material. The outer envelope 1 has a main body portion 3 and an outwardly directed cylindrical enlargement 4, the enlargement 4 of the envelope projecting outwardly from the upper portion thereof.

As shown in Figures 1 to 3, the protective element 2 has the general form of a cylinder closed at its lower end and open at its upper end. The upper open end 4' of the cylinder 4 which constitutes the attaching portion thereof, is supported within the enlargement 100

by means of a ring 5 of cement or the like, or by virtue of the provision of other yieldable supporting means between the upper end of the protective element 2 and the inner wall 5 of the enlargement 4. The cement 5 is sufficiently rigid and solid to firmly hold the protective element 2 in proper position but is sufficiently yieldable to prevent the transmission of shocks and strains between the protective element and the outer envelope. Of course, when set, the cement adheres tenaciously to both the protective element and the outer envelope.

A body of mercury designated generally at 15 6 is provided within the switch and has a portion 6^a filling the well provided by the lower closed end of the protective element and a shiftable portion 6^b which alternately unites with and divides from the portion 6^a 20 in the well. An electrode 7 is sealed in through the upper end of the outwardly displaced enlargement or supporting portion 4 of the outer envelope and projects down into the portion 6^a of the mercury. An electrode 25 8 is sealed in through one end of the outer envelope and is constantly immersed in the shiftable portion 6^b of the mercury.

To provide the opening through which the portions of the mercury may unite and divide and to shield the electrodes 7 against direct contact with the shiftable portion 6^b of the mercury, the protective element is provided with a shield 9 for the electrode 7 and with an opening 10 through which the shiftable portion 6^b of the mercury may pass. Preferably the shield 9 and opening 10 are formed prior to the assembly of the protective element with the switch and are produced by providing spaced slots in the protective element and pressing the portion of the protective element between the slots inwardly after such portion has been heated to render it sufficiently plastic to permit of this operation. Of course, when the protective element cools down it will have the structure shown in the drawings. The floor or lower wall of the lower slot which provides the opening 10 also affords an arc receiving surface 10' which may be glazed to be better adapted to stand up under the arc.

With this construction, the protective element 2 has a direct though yieldable suspension upon the upper portion of the outer envelope and the lower portion and main body of the protective element is spaced from and out of contact with the outer envelope as shown in the drawings. The organization has the further advantage of positioning the supporting portion of the outer envelope at 55 a point relatively remote with respect to the arcing zone, and it lends itself readily to a switch in which the circuit is made and broken by a mercury to mercury make and break, and wherein all danger of direct contact between the shiftable portion of the mer-

cury and the electrode connected to the other side of the circuit is precluded. It is to be understood that the outer end of the enlargement 4 of the outer envelope is open when the protective element is assembled with the outer envelope. After the protective element has been assembled and the supporting ring 5 has been built up or otherwise operatively associated with the protective element and the outer envelope, then the outer end 70 4' of the enlargement 4 is closed or fused down and the electrode 7 sealed therethrough.

While for the sake of illustration, one embodiment of the invention has been shown and specifically described, it is to be understood that various changes in the construction, shape and arrangement of the parts may be made within the spirit of the invention and the scope of the subjoined claims and particularly it is contemplated to use an inwardly 75 directed supporting member integral with the outer envelope instead of the outwardly directed supporting member 4, the inwardly directed supporting portion of the outer envelope extending into the upper open end of the protective element instead of therearound and being united thereto by a ring of cement located between its outer periphery and the inner periphery of the protective element. In other words, the supporting portion of the 80 outer envelope may be displaced laterally either outwardly or inwardly.

The invention claimed is:

1. A mercury switch comprising an outer envelope having a laterally displaced supporting portion, a protective element having one end yieldably supported thereon, said protective element being of tubular form and having its lower end closed and providing a well and having an intermediate portion partially separated from the main portion and displaced inwardly to provide an opening between the well and the interior of the envelope and to provide a shield, a body of mercury having a portion in the well and having a shiftable portion making and breaking contact with the portion in the well, an electrode sealed through the outer envelope and projecting into the well behind the shield and an electrode sealed through the outer envelope and immersed in the shiftable portion of the mercury.

2. A mercury switch comprising an hermetically sealed outer envelope, a protective element in the outer envelope having a portion partially separated from the main portion thereof and displaced relative to the main portion to provide an opening through the protective element and a shield adjacent 115 said opening, a body of mercury having portions making and breaking contact on a surface of the protective element defining the opening therethrough, and an electrode projecting down behind the shield and into the 120 125 130

portion of the mercury located below the shield.

3. A mercury switch comprising an hermetically sealed outer envelope having its upper portion formed with an outwardly directed tubular supporting member, a protective element of arc resisting material in the form of a cylinder having its upper end open and its lower end closed, the upper open end of the cylinder being fitted in the tubular supporting member and yieldably suspended therein, the lower end of the protective element being spaced from the outer envelope and defining a well, said protective element having an opening therein permitting of communication between the interior of the well and the interior of the outer envelope, and a body of mercury having a portion in the well and a portion in the outer envelope, said portions of the mercury making and breaking contact on a surface of the protective element.

4. A mercury switch comprising an hermetically sealed outer envelope having a main body provided with an outwardly directed enlargement in the upper part thereof, a protective element of arc resistant material having a portion disposed in said enlargement, yieldable supporting means between said portion of the protective element and the enlargement, all of said protective element except said portion thereof being spaced from and out of contact with said outer envelope, and a body of mercury in the outer envelope having portions uniting and dividing on a surface of the protective element.

5. A mercury switch comprising an hermetically sealed outer envelope having a laterally displaced portion in its upper part, a protective element having its upper part interfitted with and suspended on said laterally displaced portion of its outer envelope, said protective element having a well in its lower portion spaced from and out of contact with the outer envelope and also having an opening permitting of communication between the interior of the well and the interior of the outer envelope, and a body of mercury having a portion in the outer envelope and a portion in the well, said portions of the mercury making and breaking contact on a surface of the lower part of the protective element.

In witness whereof, I hereto affix my signature.

PAUL K. CRAMBLETT.
